Primary Examiner — Paula Greene(74) Attorney, Agent, or Firm — Edward L. White(57) CLAIM

The ornamental design for a handle adapted to be engaged with a latch, as shown and described.

DESCRIPTION

FIG. 1 is a front view of the handle.

FIG. 2 is a rear view of the handle.

FIG. 3 is a top view of the handle.

FIG. 4 is a bottom view of the handle.

FIG. 5 is a left-side view of the handle.

FIG. 6 is a right-side view of the handle; and,

FIG. 7 is a perspective view of the handle as it fits onto a latch.
